ELECTRICAL THERAPEUTIC APPARATUS
AND METHOD

Allen D. Cardwell, Rockville Centre, and Ralph R. Batcher, St. Albans, N. Y., assignors to Allen D. Cardwell Manufacturing Corporation, a corporation of New York

Application April 28, 1936, Serial No. 76,720

16 Claims. (Cl. 128—422)

This invention relates to electro-therapeutic apparatus.

An object of the invention is to provide a means for readily, safely and without particular skill on the part of the operator, applying electric energy for the treatment of conditions in the body which are to be relieved.

A further object of the invention is to provide means whereby desired changes in the characteristics of the energy supplied, such as frequency and/or power etc., may be effected by interchanging units each of which comprises the combination of circuit elements necessary to produce the desired conditions.

A further object of the invention is to provide a simple and readily usable means for providing different frequencies of alternating current for the part of the body affected or for the treatment of different affections.

A further object of the invention is to provide a means whereby the frequency of the applied current is quickly and accurately changed by means of interchangeable control units which may be readily inserted into or removed from

A further object of the invention is to provide, in connection with the interchangeable frequency control units, other elements carried by the control units by which other circuit functions, as for example power out-put, may be altered simultaneously with the interchanging of the units.

A further object of the invention is to provide apparatus of the character described wherein variation in the length, location or size of the leads from the apparatus to the patient will not introduce material changes in the power delivered to the patient or in the predetermined frequency thereof.

A further object of the invention is to provide means of the character as indicated which will permit of any applicators desired being used such as cutting devices, devices for coagulating, heating pads etc., all of such devices being intended to be included in the appended claims under the term "applicator."

Other and ancillary objects of the invention will appear hereinafter.

In the accompanying drawings which illustrate the invention—

Fig. 1 is a top plan view of apparatus embodying the invention;

Fig. 2 is a section on the line 2—2 of Fig. 1;

Fig. 3 is an end view looking from the right-hand end of Figs. 1 and 2;

Fig. 4 is a wiring diagram of the electrical connections;

Fig. 5 is a top plan view, partly broken away, of a modified form of unit comprising removable coil and other circuit altering elements; 5

Fig. 6 is a view similar to Fig. 5 but with a different circuit altering element; and

Fig. 7 is a view similar to Fig. 5 of a still further modification.

Referring to the drawings and first to Figs. 1 to 4 inclusive, the apparatus comprises two transformers P and F, one having its primary 1 connected through conductor 2 with one side of a suitable alternating current source of supply of suitable frequency as for instance 60 cycles, 15 while the other terminal of the primary 1 is connected through the conductor 3 and leg of the double-pole switch 4 with the other terminal of the source of supply; and the other transformer F having one terminal of its primary 5 connected through a conductor 6 and the conductor 2 with one side of the source of supply, while the other terminal of the primary is connected through the conductor 7 and the other leg of the switch 4 with the other side of the source of supply. 25

The first mentioned transformer P is for energizing the plate circuits, while the other F is for energizing the filament circuits of the thermionic vacuum tubes 12 and 13 which are employed as oscillators to give the desired high frequencies. It will be observed that the primaries of these transformers 1 and 5 are thus connected in parallel across the source of supply when the switch 4 is closed, and when the switch 4 is opened all power is removed from both transformers. 30 35

The secondary 8 of the transformer F has one of its terminals connected through the conductor 9 with one terminal of each of the filaments 10 and 11 of the oscillating tubes 12 and 13 as above 40 referred to, and the other terminal of the secondary 8 is connected through the conductor 14 with the other terminals of the filaments 10 and 11 so that the filaments 10 and 11 are connected in parallel across the transformer secondary 8. 45

The midpoint of the secondary 8 is connected through a conductor 15 and milliammeter 16 with one terminal of the transformer secondary 17, the other end of which secondary is connected by a conductor 18 with a plug contact 19. A tap 50 20 connects from an intermediate point of the secondary 17 with the stationary plug contact 21 so that when the connection is made through 19 a greater voltage will be impressed upon the circuit by the transformer secondary 17 than is the 55

case when connection is made through the contact 21.

With the arrangement shown in the wiring diagram of Fig. 4, a removable coil 22 has its terminals connected with the plug contacts 23 and 24 adapted to be plugged into the stationary contacts 25 and 26 which are respectively connected with the plates 27 and 28 of the vacuum tubes, and as the contacts 23 and 24 are plugged into the contacts 25 and 26, the contact 28 will be plugged into the contact 21 whereby an intermediate point of the coil 22 will be connected through the conductor 20 with an intermediate point of the transformer.

15 The plate circuits of the vacuum tubes will now appear as follows:

The circuit is traced from the filaments 10 and 11 of the vacuum tubes through the conductors 9 and 14 to the terminals of the secondary 8 of 20 the filament energizing transformer F, thence through the conductor 15 connected with the mid-point of the secondary 8, through the milliammeter 16 and the secondary 17 of the transformer P, thence through the conductor 20 to contacts 25 21 and 29 to the mid-point of the coil 22 whence 25 the circuit branches in opposite directions, one branch passing through the contacts 25 and 23 to the plate 27 of the tube 12 and the other branch passing through the contacts 24 and 26 30 to the plate 28 of the tube 13.

The grids 30 and 31 of the vacuum tubes are connected together through the inductance coil 32. The midpoint of coil 32 is connected through the high non-inductive resistance 33 35 and the conductor 15 with the midpoint of the transformer secondary 8 to provide a grid leak.

The grid circuit is excited by grid coil 32. It may be desirable to provide different excitation at different operating frequencies to obtain 40 optimum operating efficiency. This is accomplished by providing a grid circuit that is large enough to permit efficient operation on the lower frequencies to be used and then, if desired to reduce the excitation at any higher frequency, 45 reducing the inductance of the coil by short circuiting a portion of the coil so as to alter its effect upon the circuit. Thus a tap 34 from an intermediate point of the coil 32 is connected with the stationary contact 35, while a tap 36 50 from a point of the coil which is at the same distance from its adjacent end of the coil as is the tap 34 from its adjacent coil end, is connected with the contact 37, while upon the removable unit carrying the coil 22 are the contacts 55 38 and 39 connected by the short-circuiting conductor 40, contacts 38 and 39 being adapted to be respectively plugged into the contacts 35 and 37 when the unit carrying the coil 22 and the contacts 23, 38, 29, 39 and 24 are placed in position, the contacts 23, 38, 29, 39 and 24 being 60 respectively and simultaneously plugged into the stationary contacts 25, 35, 21, 37 and 26. Or, a certain portion of the grid coil 32 may be shunted 65 with an inductance as in Fig. 6. Or, similar results may be accomplished by using a grid coil smaller than that necessary for the lower frequencies and to shunt all or a portion of it with a condenser 56 as in Fig. 5, when such low frequency output coils are being used.

70 Adjustably coupled with the coil 22 is an output coil 41 to the terminals of which are connected the leads 42 and 43 leading to the applicators 44 and 45 which may consist of conductors 75 enclosed in rubber pads, electrical cutting im-

plements or any means by which the energy is applied to the part desired.

While the applicator leads 42 and 43 are shown as connected to the extremities of the coil 41, such coil might be provided with any 5 desired number of intermediate taps 74 located at different points along the coil to which a lead 42 or 43 could be selectively connected thereby including such portion of the coil as is desired between the leads.

10 The mechanical arrangement of the apparatus may be as shown in Figs. 1, 2 and 3 wherein upon the base 46 are mounted the transformers P and F. Also mounted upon the base are the vacuum tubes 12 and 13 having their axes vertical and the grid coil 32 with its axis horizontal. Also upon the base is mounted a frame or support 47 of wood or other suitable insulating material upon an insulating strip on which are mounted the contacts 25, 35, 19, 21, 37 and 26.

15 Sliding upon the guides 48 is a carrier 49 of porcelain or other suitable insulating material comprising the handle portion 50, and in the hole 53 of which is mounted the inductance coil 22 having its terminals connected with the contacts 23 and 24 as before described, these contacts 23 and 24 and also the contacts 38, 29 and 37 being mounted upon the porcelain carrier whereby they are suitably insulated from each other and adapted to plug into the contacts 25, 30 35, 21, 37 and 26 when the porcelain carrier or frame with its carried inductance coil are inserted into position in the frame. The coil 41 is fixed on a shaft 51 rotatably mounted on the support 47 and provided with a knob 52 by which 25 it may be turned. The output coil 41 may thus be turned into its extreme uncoupled position as shown in Figs. 1, 2 and 3 or, by turning the shaft 51, the coil 41 may be moved down within the coil 22 to any desired extent.

40 When the carrier 49 carrying the coil 22 has been inserted in position upon the frame and the contacts engaged as described, and the shaft 51 has been turned to turn the coil 41 downwardly to an operative position within the coil 22, the 45 round-ended projection 54 fixed upon the shaft will have come into engagement with the spring latch 55 secured at one end to the support 47 which will thus be pushed downwardly so as to latch back of the carrier 49 and prevent the removal of the carrier 49. When, however, it is desired to interchange the carrier, the shaft 51 is turned to elevate the coil 41 into the position as shown in Fig. 2, when the latch 55 will be released from the projection 54 and will spring 55 up (see Fig. 2) so as to permit the carrier 49 to be slid out of the support. It will thus be seen that it is impossible to remove the carrier 49, which involves the breaking of connection with the coil 22 and other carried apparatus, while 60 the output coil 41 is in operative relation to the coil 22, but that the output coil must be moved into uncoupled relation before the carrier can be removed.

65 To automatically disconnect the supply circuit when a carrier 49 is removed and to close such circuit when the carrier is placed in operative position, normally open spring contacts 76 are inserted in the supply line 3. These contacts are adapted to be closed when a plunger 77 is inserted between them. The plunger reciprocates in a cylinder 78 mounted on the support 47 and tends to be retracted out of connecting position by a spring 79. When a carrier 49 is inserted 70 into operative position it abuts against the end 75

of the plunger and pushes it against the pressure of the spring so that it engages and connects the contacts 70 and conversely, when the carrier is withdrawn the spring retracts the plunger and opens connection between the contacts.

The various parts of the circuits are so proportioned and arranged that the desired high frequency is applied to the applicators and the energy applied is regulated by the turning of the shaft 51 by the knob 52 whereby the coupling of the output coil 41 with the coil 22 is varied at the will of the operator. It is advocated, however, that different frequencies be used for different ailments, and to this end there may be a plurality of carriers as 49 having coils 22 of different numbers of turns, and therefore of different inductance, respectively, or coils shunted with various capacities, and these coils may be interchanged in the apparatus by removing a carrier 49 carrying one coil 22 and inserting another carrier carrying a coil having a different number of turns or shunted by a different capacity. By thus interchanging the coils the frequency of the voltage in the output to the applicators is altered and this alteration may be such as to suit the treatment in hand. The interchange of the coils 22 as described to obtain the desired frequencies by the insertion and removal of the carrier which also automatically effects the necessary connections, provides a simple means whereby even a person unskilled in electricity may effect the proper adjustments. It may not even be necessary for the physician or other operator to know at what frequency he is working. It has been quite definitely established in relation to certain ailments that a certain frequency is required and a carrier 49 carrying a suitable coil 22 and other equipment giving that frequency may be labeled with the name of the ailment, so that in making a treatment the operator simply inserts into the support 47 the carrier 49 which is labeled with the ailment to be treated when the proper conditions will be realized with small knowledge on the part of the operator of the nature of the electrical actions involved.

The output circuit, including the applicators and the coil 41, may be attuned to resonance if desired and the applicators located at potential nodes. It has been found when this is done that the length, size and position of the leads must be definitely fixed. With the arrangement shown the length of leads from the output coil to the applicators may be varied anywhere from three to six feet or more without introducing changes in the power delivered even though the portion of the body of the patient in the field is relatively short with respect to the lengths of the leads, by using a coupling coil with a relatively large number of turns whereby a large voltage can be induced even though the circuit is not resonance. The use of a non-resonant circuit as described, eliminates the need for leads of fixed definite lengths. Variation in the load requirement due to the application of the pads at different positions, changes in the area and spacing of the pads, and necessary changes in the power requirements due to the nature of the treatment, all can be compensated for by altering the coupling between the plate circuit coil and the output circuit coil. It is to be noted that the output circuit is electrically insulated from the high voltage circuit which eliminates the danger

of the operator or the patient receiving electrical shocks.

It is found that each frequency requires the changes of certain circuit constants. According to the present invention all these changes necessary to produce the desired result are produced by insertion of a single unit whereby the care and skill required of the operator is reduced to a minimum; for instance, it may be that some of the coils 22 inserted in the apparatus may change the circuit constants so as to require a corresponding change in the constants of the grid circuit; thus, a coil 22 may be such that instead of the short-circuiting conductor 40 a suitable capacity be connected across the portion of the coil 32 to produce the desired conditions. Accordingly a condenser 56 mounted upon the carrier 49 may have its terminals connected with the contacts 38 and 39, so that upon inserting the carrier in operative position the condenser (in place of the short-circuiting conductor 40) will be connected by the conductors 34 and 36 across the portion of the grid coil 32, the other connections established being as described.

In some instances the desired conditions might be realized in connection with the output coil carried by the carrier 49 by connecting an inductance 57 across a portion of the coil 32 by the conductors 34 and 36. Accordingly an inductance coil 30 57 is mounted upon the carrier 49 and has its terminals connected with the contacts 38 and 39 in place of the short-circuiting conductor 40, the other connections being as before described.

In still other circumstances it may be desirable to change the effective amount of the resistance 33 in circuit, and to this end two additional contacts 58 and 59 are mounted upon the carrier 49 with corresponding stationary plug contacts 60 and 61, the contact 61 being connected by conductor 62 with an intermediate point of the resistance 33 while the contact 61 is connected by a conductor 63 with an end of the resistance 33. The contacts 58 and 59 are connected by a short circuit conductor 64 mounted on the carrier 49 so that when the carrier 49 is placed in position the portion of the resistance 33 between the points of connection of the conductors 62 and 63 is short-circuited and thereby cut out of action to effect the desired relationships.

It is to be observed that in Fig. 4 the center point of the coil 22 is connected through the tap 20 with an intermediate point of the transformer secondary 17, whereby less than the whole secondary voltage is applied. As it is desirable to increase the plate voltage at some of the lower frequencies or with certain applications, this can be accomplished, in carriers having a coil 22 for such lower frequencies, by connecting the intermediate point of that coil with the contact 65 (as indicated in dotted lines in Fig. 4) instead of with the contact 29, when the connection will be established through the contact 19 and conductor 18 with the end of the secondary 17, so that the voltage impressed will be increased over that where the connection is made to the intermediate point of the transformer secondary 17 by the conductor 20.

While the invention has been illustrated in some of its applications it may have other embodiments without departing from its spirit and is not therefore limited to the structures shown in the drawings.

What we claim is:

1. In electro-therapeutic apparatus, the combination with a circuit including an oscillator and a coil adapted to be connected and disconnected in the circuit to control the frequency of the current applied to a patient, of an output coil inductively coupled with the first mentioned coil and movable with relation thereto to control the coupling therebetween and an applicator connected with said output coil, said output coil being movable into and out of the first mentioned coil when the latter is in operative position whereby the first mentioned coil is prevented from disconnection while the said output coil is in position to be within the first mentioned coil.
2. In electro-therapeutic apparatus, the combination with a circuit including an oscillator and a coil adapted to be connected and disconnected in the circuit to control the frequency of the current applied to a patient, of an output coil inductively coupled with the first mentioned coil and movable with relation thereto to control the coupling therebetween and an applicator connected with said output coil, the output circuit being non-resonant with relation to the first mentioned circuit, said output coil being movable into and out of the first mentioned coil when the latter is in operative position whereby the first mentioned coil is prevented from disconnection while the said output coil is in position to be within the first mentioned coil.
3. In electro-therapeutic apparatus, the combination with a circuit including an oscillator and having contacts connected thereto and a unitary member having a coil adapted to control the frequency of the current applied to a patient and connected with contacts on said unitary member adapted to engage with the first mentioned contacts when the said unitary member is placed in position, of a movable output coil inductively coupled with the first mentioned coil when the said unitary member is in connected position, to control the coupling between the said coils and an applicator connected with said output coil, said output coil being movable into and out of the first mentioned coil when the latter is in operative position whereby the first mentioned coil is prevented from disconnection while the said output coil is in position to be within the first mentioned coil.
4. In electro-therapeutic apparatus, the combination with a circuit including an oscillator and having contacts connected thereto and a unitary member having a coil adapted to control the frequency of the current applied to a patient and connected with contacts on said unitary member adapted to engage with the first mentioned contacts when the said unitary member is placed in position, of an output coil inductively coupled to the first mentioned coil when the said unitary member is in connected position, to control the coupling between the said coils and an applicator connected with said output coil and an element for altering a constant of the first mentioned circuit, said element being mounted on said unitary member, contacts on said unitary member to which said element is connected and stationary contacts connected with the last mentioned circuit and adapted to be engaged by the contacts connected with said element when said unitary member is placed in position and disengaged therefrom when said unitary member is removed from operating position.
5. In electro-therapeutic apparatus, the com-

bination with a circuit including an oscillator and a coil adapted to be connected and disconnected in the circuit to control the frequency of the current applied to a patient, of an output coil inductively coupled with the first mentioned coil and movable with relation thereto to control the coupling therebetween and an applicator connected with said output coil and means for preventing the disconnection of the first mentioned coil when said output coil is in operative coupling relation thereto.

6. In electro-therapeutic apparatus, the combination with a circuit including an oscillator and a coil movable into and out of operative relation to said circuit and an output coil inductively coupled with the first mentioned coil and movable with relation thereto to control the coupling therebetween and an applicator connected with said output coil, of means controlled by the position of said output coil for controlling the removal of said first mentioned coil from operative position.

7. In electro-therapeutic apparatus, the combination with a circuit including an oscillator and having contacts connected thereto and a unitary member movable into and out of operative position and having a coil adapted to control the frequency of the current applied to a patient and connected with contacts on said unitary member, said contacts being adapted to engage, with the first mentioned contacts when the said unitary member is placed in position, of an output coil inductively coupled with the first mentioned coil when the said unitary member is in operative position, an applicator connected with said output coil and means controlled by the position of said output coil with relation to the first mentioned coil for preventing the removal of said unitary member from operative position.

8. In electro-therapeutic apparatus, the combination with a circuit including a thermionic vacuum tube oscillator and a grid circuit and having contacts connected thereto and a unitary member having a coil adapted to control the frequency of the current applied to a patient and connected with contacts on said unitary member adapted to engage with the first mentioned contacts when the said unitary member is placed in position, of an output coil inductively coupled to the first mentioned coil when the said unitary member is in operative position and movable to control the coupling between the said coils, an applicator connected with said output coil and an element for altering a constant of the said grid circuit, said element being mounted on said unitary member, contacts on said unitary member to which said element is connected and stationary contacts connected with the said grid circuit and adapted to be engaged by the contacts connected with said element when said unitary member is placed in position and disengaged therefrom when said unitary member is removed from operating position.

9. In electro-therapeutic apparatus, the combination with a circuit including a thermionic vacuum tube oscillator having a plate circuit, contacts connected with said plate circuit and a unitary member movable into and out of operative position and having a coil adapted to be connected in the said plate circuit to control the frequency of the current applied to a patient and connected with contacts on said unitary member adapted to engage with the first men-

tioned contacts when the said unitary member is placed in operative position, of an output coil inductively coupled to the first mentioned coil when the said unitary member is in connected position to control the coupling between the said coil and an applicator connected with said output coil, said output coil being movable into and out of the first mentioned coil when the latter is in operative position whereby the first mentioned coil is prevented from disconnection while the said output coil is in position to be within the first mentioned coil.

10. In electro-therapeutic apparatus, the combination with a circuit including an oscillator having plate and grid circuits, contacts connected thereto and a unitary member having a coil adapted to control the frequency of the current applied to a patient and connected with contacts on said unitary member adapted to engage with contacts connected with said plate circuit when the said unitary member is placed in operative position, of an output coil inductively coupled to the first mentioned coil when the said unitary member is in operative position and movable to control the coupling between the said coils and an applicator connected with said output coil and an element for altering a constant of the said grid circuit, said element being mounted on said unitary member, and contacts on said unitary member to which said element is connected and adapted to be engaged by contacts connected with said grid circuit when said unitary member is placed in position.

11. In electro-therapeutic apparatus, the combination with a circuit including an oscillator and a unit comprising a coil adapted to be connected and disconnected in the circuit, to control the frequency of the current applied to a patient, of an output coil inductively coupled with the first mentioned coil and movable with relation thereto to control the coupling therebetween and an applicator connected with said output coil, a supply circuit and means controlled by said unit for controlling said supply circuit.

12. In electro-therapeutic apparatus, the combination with a circuit including an oscillator, of a selected master control unit connectible and disconnectible in the said circuit, said unit determining the frequency applied to a patient and other circuit elements and contacts carried by said unit for controlling conditions in the oscillator circuit whereby such conditions are kept at optimum effectiveness for that frequency.

13. The method of varying the frequency of electric energy applied in therapeutic treatment, which energy is derived from a circuit containing an oscillator and an application circuit inductively coupled with the aforesaid circuit, which consists in interchanging coupling coil units in the first mentioned circuit applying the energy of said application circuit to a patient and varying the voltage of the said application circuit by varying the inductive coupling between said application circuit and the said circuit containing an oscillator.

14. The method of varying the electric energy applied in therapeutic treatment, which energy is derived from a circuit containing an oscillator and an application circuit inductively coupled with the aforesaid circuit, which consists in disconnecting a coupling coil unit from the first mentioned circuit and connecting another coupling coil unit in the first mentioned circuit in place of the disconnected coil unit, applying the energy of said application circuit to a patient and varying the voltage of the said application circuit by varying the inductive coupling between said application circuit and the said circuit containing an oscillator.

15. The method of varying the characteristics of electric energy applied in therapeutic treatment, which energy is derived from a circuit containing an oscillator, which method consists in interchanging frequency determining units in said circuit by disconnecting a frequency-determining unit from said circuit and connecting another frequency-determining unit to said circuit in place of the disconnected unit, applying the energy of said application circuit to a patient and varying the voltage of the said application circuit by varying the inductive coupling between said application circuit and the said circuit containing an oscillator.

16. In electro-therapeutic apparatus, the combination with a circuit including an oscillator and a unit comprising a coil adapted to be connected and disconnected in the circuit, to control the frequency of the current applied to a patient, of an output coil inductively coupled with the first mentioned coil and movable with relation thereto to control the coupling therebetween, an applicator connected with said output coil, a supply circuit and a switch controlled by said unit for controlling said supply circuit.
